UNITED STATES PATENT OFFICE.

JOSEPH ALBERT, OF BROOKLYN, NEW YORK.

DETACHABLE LINING.

1,363,209.

Specification of Letters Patent. Patented Dec. 28, 1920.

Application filed September 1, 1920. Serial No. 407,422.

To all whom it may concern:

Be it known that I, JOSEPH ALBERT, a citizen of the United States, residing at Brooklyn, in the county of Kings and State 5 of New York, have invented new and useful Improvements in Detachable Linings, of which the following is a specification.

This invention relates to garments, and more specifically to an improvement in detachable linings for waists and other garments of a similar nature.

In my co-pending application filed February 9, 1920, Serial No. 357,131, I have shown a garment comprising a sleeveless 15 waist having a lining detachably located therein and provided with sleeves which are detachably secured to the lining. This invention relates to an improvement upon the article disclosed in my other application, as 20 above identified, and has as one of its primary objects the provision of improved means for securing and positioning the lining within the garment.

Another object of the invention is to provide a lining which may be used in garments of varying size by providing means whereby the lining may be adjusted and may at the same time be concealed at the point where it is so adjusted in size.

Another feature of the invention is the provision of a garment construction whereby a detachable lining may be placed in garments in which the waist is given a blouse effect, or in which an overskirt is 35 provided. The above, and other objects of the invention which are of a more obvious nature and which will become manifest as the description proceeds, are attained by constructing a waist having an interior flap 40 at the neck adapted to fold over the upper edge of the detachable lining. Fastener elements are located upon the flap and upon the lining and the lining is provided with means whereby it may be taken up and adjusted in size beneath the flap, this means 45 being shown specifically as a line of perforations extending between the fastener elements so that the lining may be folded over the fastener elements with the fastener elements extending through the perforations.

Referring to the accompanying drawings, wherein one embodiment of my invention is shown by way of example,

Figure 1 is a perspective of a waist pro-

vided with a lining, a portion of the waist 55 being broken away to show the connection of the sleeves to the lining,

Fig. 2 is a front elevational view of the lining with the sleeves secured thereto, one of the sleeves being partly detached from 60 the lining,

Fig. 3 is an interior view of one of the sleeve extensions,

Fig. 4 is an edge view of a modified form 65 of garment taken along the opening line of the garment and showing a garment having a waist and skirt portion with an inner facing secured thereto so that the waist may be given a blouse effect.

Fig. 5 is a view of the upper portion of 70 the waist shown in Fig. 1 with the flap raised and showing the lining folded over so that excessive fullness may be taken up.

Referring to the drawings more in detail, 75 10 indicates a sleeveless waist having a lining 11 therein which is detachably secured to the waist by means hereinafter described. The waist is shown as being sleeveless, and the lining itself is of sleeveless construction, but sleeve members 12, which may or may 80 not match the waist in texture and color, are detachably secured to the lining. Referring to Fig. 3, it will be noted that these sleeves are formed with extensions 13 each extending upon the shoulders and over the 85 body around the arms. The sleeve members may be attached to the lining in any suitable manner, but in the present instance they are shown as being detachable, the sleeve extensions having fastener elements 90 14 upon their interior faces, and the lining having located thereon a line of complementary fastener elements 15 extending down the front of the lining and up over the shoulder. It will be noted that the sleeve 95 extensions are not secured to the lining at the back below the shoulders, they being held in position by means of an elastic element 16 secured at each end to the sleeve extensions and extending across the back. 100

The lining, constructed as above described, may be secured within the waist in any manner desired but it is preferable that the lining be made detachable from the waist so that it may be laundried when 105 necessary. In the drawings I have shown the waist as being formed at the neck with an interior flap 17 adapted to fold over the

upper edge of the lining, thereby positioning and concealing the same. Of course, the lining may be directly secured to the waist but for the sake of appearance and simplicity of structure it is preferable that it be secured to the flap 17. Any practicable form of fastener element may be used but in the specific embodiment of my invention shown in the drawings I have shown the flap as being provided upon its under face with sockets 18 which coöperate with complementary posts 19 adapted to fit within the sockets. Obviously other forms of securing means might be employed for holding the lining within the waist and also the fastener elements might be placed upon the outer face of the flap, the flap not being folded over the upper edge of the lining. It will be noted that when the flap is folded over and the fastener elements engaged, as shown in Fig. 1, the lining is firmly secured in position within the waist and its upper edge is neatly and effectively held in position so that it cannot extend up above the upper edge of the waist at the neck.

By reference to Figs. 2 and 5 it will be noted that the lining has a plurality of perforations 20 adjacent the fastener elements and shown as extending between them, although they might be located on each side of the fastener elements. These perforations may be formed by hemstitching and coöperate with the fastener elements to permit the adjustment of the lining to conform to the size of the waist. If it is found that the lining is slightly large for the waist it may be folded over as shown in Fig. 5 so that perforations at any selected distance from the fastener elements will be brought over and positioned above the posts 19 so that the posts project through these perforations. By thus folding the lining excessive fullness is taken up and the flap 17 may then be folded downwardly to cover the folds and to bring the sockets 18 and posts 19 into engagement.

It may be found desirable to place a plurality of sockets in the flap so that if any considerable adjustment is made in the lining and the position of the posts 19 changed, the posts will be positioned beneath other of these sockets into which they may be inserted without ruffling the flap.

Referring to Fig. 4, there is shown an edge view of a modified form of garment, the view being taken along the line of opening of the garment, which comprises a waist portion 21, a skirt 22 and an interior facing 23. The facing 23 is secured to the waist at the neck 24 by folding over the upper edge of the waist, and may be secured to the skirt and waist by a line of stitching 25, the stitching being run after the skirt is slightly lifted in order to give the waist the blouse effect shown. The fas-

tener elements shown upon the inner face of the waist coöperate with complementary fastening members upon the edge of the waist at the other side of the opening, and the fastener elements shown upon the facing coöperate with complementary fastener members which may be placed in suitable positions along the lining. Such fastener members are not shown in the lining disclosed in Figs. 1 and 2, but, obviously, might be positioned thereon when desired.

The garment thus constructed may have the detachable lining shown in Figs. 1 and 2 secured therein in the same manner indicated in Fig. 1. I am aware that it is not broadly new to provide a detachable lining but, so far as I am aware, I am the first to devise a garment having a blouse effect together with a detachable lining. It is, of course, evident that by providing the interior facing 23 numerous other variations of garment construction may be adopted, such as the provision of an overskirt, all of which come within the scope of my invention. It will be understood that the constructions shown in the accompanying drawings are shown merely by way of example and that my invention may take other forms, all of which come within its scope as defined by the following claims:

1. In a garment, an outer waist, a lining for the waist, and means for detachably securing the lining within the waist comprising an interior flap upon the waist adjacent the neck adapted to fold over the upper edge of the lining, a fastener element on said flap and a fastener element upon the lining beneath said flap.

2. In a garment, an outer waist, a lining for the waist, and means for detachably securing the lining within the waist comprising an interior flap upon the waist adjacent the neck adapted to fold over the upper edge of the lining, a fastener element on said flap, a fastener element upon the lining beneath said flap, and means for adjusting the size of the lining at the neck.

3. In a garment, an outer waist, a lining for the waist, and means for detachably securing the lining within the waist comprising an interior flap upon the waist adjacent the neck adapted to fold over the upper edge of the lining, fastener elements on said flap, fastener elements upon the lining beneath said flap, said lining having a plurality of perforations adjacent the fastener elements whereby excessive fullness in the lining may be taken up substantially as set forth.

4. In a garment, an outer sleeveless waist, a detachable lining for said waist, sleeves for the waist, means for detachably securing the sleeves to the lining, and means for detachably securing the lining within the waist comprising an interior flap upon the waist adjacent the neck, said flap folding over and

- positioning the upper edge of the lining, a fastener element upon the flap and a complementary fastener element upon the lining beneath said flap.
5. 5. In a garment, an outer sleeveless waist, a detachable lining for said waist, sleeves for the waist, means for detachably securing the sleeves to the lining, and means for detachably securing the lining within the waist
- 10 comprising an interior flap upon the waist adjacent the neck, said flap folding over and positioning the upper edge of the lining, a fastener element upon the flap and a complementary fastener element upon the lining beneath said flap, said lining having a plurality of perforations adjacent said fastener element whereby the size of the lining may be selectively varied substantially as set forth.
- 20 6. In a garment having an outer waist, a skirt, an inner facing member secured to said waist and skirt, a lining for said waist, and means for detachably securing said lining within the waist.
- 25 7. In a garment having an outer waist, a skirt, an inner facing member secured to said waist and skirt, a lining for said waist, and means for detachably securing said lining within the waist comprising an interior flap upon the waist adjacent the neck adapted to fold over the upper edge of the lining, fas-

tener elements upon the flap and fastener elements upon the lining beneath said flap.

8. In a garment, an outer waist, a lining for the waist, and means for detachably securing the lining within the waist comprising an interior flap upon the waist adjacent the neck and fastening means for securing the lining to the flap. 35

9. In a garment, an outer waist, a lining for the waist, means for detachably securing the lining within the waist comprising an interior flap upon the waist adjacent the neck, means for securing the lining to the flap, and means for adjusting the size of the lining at the neck. 40

10. In a garment, an outer waist, a lining for the waist, means for detachably securing the lining within the waist, and means for adjusting the size of the lining adjacent the neck. 50

11. In a garment, an outer waist, a lining for the waist, means for detachably securing the lining within the waist at the neck, means for adjusting the size of the lining 55 at the neck, said adjusting means comprising a line of perforations in the lining and fastener elements adapted to coöperate therewith.

In testimony whereof I have hereunto set 60 my hand.

JOSEPH ALBERT.
